UNITED STATES PATENT OFFICE.

JOHN A. HARRISS, OF NEW YORK, N. Y.

DESIGN FOR A STORE-FRONT.

56,429.

Specification for Design.

Patented Oct. 26, 1920.

Application filed March 17, 1920. Serial No. 366,709. Term of patent 14 years.

To all whom it may concern:

Be it known that I, JOHN A. HARRISS, a citizen of the United States, residing at New York city, in the borough of Manhattan, county and State of New York, have invented a new, original, and ornamental Design for a Store-Front, of which the following is a specification, reference being had to the accompanying drawing, forming part thereof.

In the drawings, Figure 1 is a front elevation, and Fig. 2 a side elevation, showing my new design.

I claim:

The ornamental design for a store front, as shown.

JOHN A. HARRISS.
